(*) Notice: This patent is subject to a terminal disclaimer.

(57) **CLAIM**

The ornamental design of a one piece plastic extrusion having a co-extruded foam core for a hurricane or storm shutter, as shown and described.

(**) Term: **14 Years**

DESCRIPTION

(21) Appl. No.: **29/163,462**

(22) Filed: **Jul. 8, 2002**

(51) LOC (7) Cl. **25-02**

FIG. 1 is a perspective view of a one piece plastic extrusion having a co-extruded foam core for a hurricane or storm shutter, showing our new design, with a middle portion broken away to disclose indefinite length; and,

(52) U.S. Cl. **D25/47**

(58) Field of Search 160/133, 130, 160/41, 185, 238; D25/47, 49, 119, 124

FIG. 2 is an end view thereof, the opposite end view being a mirror image.
